UNITED STATES PATENT OFFICE.

RALPH S. CLARKE, OF WALPOLE, MASSACHUSETTS, ASSIGNOR TO BIRD MACHINE COMPANY, A CORPORATION OF MASSACHUSETTS.

SAVE-ALL.

1,338,211.

Specification of Letters Patent. Patented Apr. 27, 1920.

Application filed July 23, 1919. Serial No. 312,875.

To all whom it may concern:

Be it known that I, RALPH S. CLARKE, a citizen of the United States, residing at Walpole, in the county of Norfolk and State 5 of Massachusetts, have invented certain new and useful Improvements in Save-Alls, of which the following is a specification.

This invention pertains to save-alls for paper machines, and has reference more particularly to the means employed for regulating or controlling the water supply which passes to the shower pipe employed in conjunction with the screen.

The invention is illustrated in the annexed 15 drawings, wherein:

Figure 1 is an end elevation of the machine;

Fig. 2 a side elevation thereof;

Fig. 3 a detail sectional elevation of the 20 float controlled shaft and the allied valve operating parts; and

Fig. 4 a sectional plan illustrative of the float connections.

In said drawings, 1 denotes the vat having 25 an inlet 2 and an overflow 3, the latter opening into a lateral extension 4 of the vat or tank. The screening cylinder is denoted by 5 and the discharge from the interior thereof takes place through the outlet 6. The 30 retained pulp is removed from the machine by a centrifugal pump 7, as is usual.

The screen is carried by suitable bearings and the hollow supporting shaft 8 thereof at the right in Fig. 2 has secured thereto a 35 large driving gear 9. A suitable stub shaft 10 carries a driving pinion 11 which meshes with gear 9, said shaft also carrying a pulley wheel 12 about which passes a belt 13. Said belt in turn passes about a second and 40 smaller pulley wheel 14 mounted to rotate upon a fixed shaft 15, the inner end of which is secured in a bracket 16 secured to the side wall of the tank extension 4, see Fig. 3. A band wheel 17 secured to the pulley 14 is 45 driven by a constantly driven power belt 18 and serves through pulley 14 and belt 13 to impart movement to band wheel 12 and to the screen through pinion 11 and gear 9. Belt 13 is of such length that when slack no 50 motion is imparted to the screen and means is provided which is controlled by the height of the liquid within the tank for tensioning the said belt, said means also controlling the supply of water to the spray pipe.

55 Journaled on the shaft 15 intermediate

the bracket 16 and pulley 17 is a sleeve-like member 19 provided with a downwardly extending arm or lever 20. Said arm at its lower end has fixedly mounted therein a laterally extending shaft 21 upon which is 60 journaled a wheel 22 which stands in line with and bears against the belt 13, said wheel tending to tension the belt as the arm 20 is swung or moved inwardly toward the belt. Such movement is effected by the rising and falling of a float 23 which is located within the tank extension, the float being attached to the lower end of a lever 24, the opposite end of which is secured in an arm 25 formed as an extension of a hub 26, which 65 embraces and is secured to the sleeve 19. As the level of the water rises and falls within the tank and extension 4, the float is carried therewith, the rise causing the float through the parts just described, to rotate sleeve 19 70 and to swing arm 20 inwardly forcing roller 22 against belt 13 and placing the same under tension. At such time the screen will be rotated at its highest speed. As the water level drops, for one or another reason, 75 the float also moves with it and consequently the roller 22 tends to move away from belt 13, lessening the tension thereof and lowering the speed of rotation of the screen. When the float reaches the lowest level the 80 roller will be in such position that all active pressure on the belt is removed and the 85 screen comes to rest.

Mounted within the screen is a spray pipe 27, said pipe being carried by arms 28, the 90 inner ends of which are secured to the wash water supply pipe 29 which extends axially through the machine, a branch 30 extending therefrom to the spray pipe. A valve 31 is connected into the outer end of the 95 supply pipe and a valve-operating-lever 32 is connected thereto. Said lever is connected by a draw rod or bar 33 to a second lever 34 which latter is fixedly attached to the outer end of shaft 21. As a consequence 100 of such arrangement, as arms 20 and 34 (which move as one) swing under the action of the rising or falling of the float, the valve will be opened and closed to a greater or less extent. As the movement of the 105 float controls the speed of the screen, it will be seen that the amount of water which will pass to and through the spray pipe 27 will be regulated in accordance with such screen movement, the greater the screen speed the 110

greater the amount of water which passes through valve 31 to the spray pipe and, conversely, as the screen speed falls the water is proportionally cut off from the spray 5 pipe. In other words, the current of water which passes to the spray pipe is directly proportional to the speed of the screen travel, and such speed and supply are automatically controlled and regulated by the 10 level of the water in the tank.

15 The degree of opening and closing of the valve may be regulated by adjusting the point of connection of rod 33 to the levers 32 and 34. The fiber which is gathered by 20 the screen is driven off by the shower and falls into a compartment 35 from which it will be pumped to the point where it is to be used.

What is claimed is,—

25 1. In a machine of the class described, the combination of a tank; a screen mounted for rotation therein; a spray pipe adapted to project a shower against the screen surface; and means controlled by the level of 30 the water in the tank for regulating the speed of rotation of the screen and the flow of water through the spray pipe.

35 2. In a machine of the class described, the combination of a tank; a screen mounted for rotation therein; a spray pipe adapted to project a shower against the screen surface; and float actuated means controlled by the level of the water in the tank for regulating the speed of rotation of the screen 40 and the flow of water through the spray pipe.

3. In a machine of the class described, the combination of a tank; a screen mounted for rotation therein; a spray pipe adapted 45 to project a shower against the screen surface;

face; and means controlled by the level of the water in the tank for directly regulating the amount of water which may pass to the spray pipe.

4. In a machine of the class described, the 45 combination of a tank; a screen mounted for rotation therein; a spray pipe adapted to project a shower against the screen surface; a valve controlling the supply of water to said pipe; variable driving means for 50 the screen; and means controlled by the level of the water in the tank for simultaneously regulating the valve and said driving means.

5. In a machine of the class described, the 55 combination of a tank; a screen mounted for rotation therein; a spray pipe adapted to project a shower against the screen surface; a valve controlling the supply of water to said pipe; variable driving means for 60 the screen; and float actuated means controlled by the level of the water in the tank for simultaneously regulating the valve and said driving means.

6. In a machine of the class described, the 65 combination of a tank; a screen mounted for rotation therein; a spray pipe adapted to project a shower against the screen surface; a valve controlling the supply of water to said pipe; a constantly driven power 70 element; a belt wheel in driving connection with the screen; a loose belt extending therefrom to the driven element aforesaid; a float controlled belt tightener acting thereon; and connections between said tightener 75 and the valve for opening and closing the same.

In testimony whereof I have signed my name to this specification.

RALPH S. CLARKE.
